UNITED STATES PATENT OFFICE.

LEWIS J. TETLOW, OF WEST SPRINGFIELD, MASSACHUSETTS.

AERIAL MACHINE.

1,114,311.

Specification of Letters Patent. Patented Oct. 20, 1914.

Application filed December 23, 1912. Serial No. 738,117.

To all whom it may concern:

Be it known that I, LEWIS J. TETLOW, a citizen of the United States of America, and resident of West Springfield, in the county of Hampden and State of Massachusetts, have invented certain new and useful Improvements in Aerial Machines, of which the following is a full, clear, and exact description:

This invention relating to improvements in aerial machines or vessels is characterized by the provision of one or more aeroplanes mounted above the supporting frame and so jointed as to be tiltable transversely against mediums of yielding resistance which have a tendency to maintain the planes normally with one side at the same height as the other, such aeroplanes, of course, having means for varying their fore-and-aft inclinations; and in the machine as preferably constructed having two aeroplanes, one at the forward and the other at the rearward portion of the machine, the latter named means is operable for simultaneously operating both of the planes in corresponding degrees of inclination.

The machine is furthermore characterized by provisions whereby the transversely tiltable and longitudinally rocking aeroplanes are balanced for most satisfactory results.

The machine is further characterized by an aeroplane machine having motors mounted on longitudinally movable adjustable supports therefor forward and to the rear of the center of gravity of the machine with means for effecting longitudinal adjustments of the motor supports and for confining them in their properly adjusted positions.

The machine is, furthermore, characterized by an organization of parts especially inclusive of aeroplanes in fore-and-aft relations, propellers at the front and rear portions of the machine, the movably mounted motors, the centrally located rudder staff or shaft, and respective means for controlling the actions of the various instrumentalities.

The invention is described in conjunction with the accompanying drawings and is set forth in the claims.

In the drawings:—Figure 1 is a plan view of the machine; Fig. 2 is a side elevation of the same; Fig. 3 is a view showing parts comprised in and pertaining to the longitudinally movable motor suspension sup-

port. Fig. 4 is a cross sectional view in detail of a portion of one of the aeroplanes. Fig. 5 is an end elevation of the machine, the propeller being omitted. Fig. 6 represents details of construction comprised in the means for effecting fore-and-aft inclination of either one of the aeroplanes. Figs. 7 and 8 are views as seen at right angles to each other, of the upstanding support for each aeroplane and the peculiar means by which the aeroplane is jointed and adjustable, relatively to the upstanding support. Figs. 9 and 10 are respectively a side elevation and a vertical sectional view on line 10—10, Fig. 9, showing details of construction pertaining to the depending balancing and ballasting members provided at lateral parts of each aeroplane. Fig. 11 is a side elevation of the operating device securing the inclinations of the aeroplanes. Fig. 12 is a partial plan view of the structural feature comprised in the frame of the machine.

Similar characters of reference indicate corresponding parts in all of the views.

In the drawings, A represents the frame of the machine, the same being of a skeleton or openwork construction and of any suitable design, and material consistent with lightness.

The machine as organized according to the drawings comprises two aeroplanes B B which are represented as considerably wider at the forward portion than at the rear.

D D represent upstanding supports or posts located at the longitudinal median of the frame, one forward and the other some what behind the middle of the machine.

Each aeroplane has at the forward part thereof on its central longitudinal line a bracket a comprising a longitudinal downwardly open slideway a² and shaft supports a³ to the forward and rear of the slideway. The bracket is secured by bolts or in any suitable manner at the underside of the aeroplane. The block b is fitted and guided for movement in the slideway; and a screw shaft d, rotatively mounted in said shaft supports a³ has a screw engagement through the block so that by the turning of the screws an adjusting movement of the block along the length of the aeroplane may be acquired. A universal joint e connects the block and the upstanding support or post so that while the aeroplane may be rocked for any fore-and-aft inclination, it may also be tilted transversely. The transverse rock-

ing movement of each aeroplane is against the resistance of resilient means serving as opposite elastic connections between the frame, or some appliance at the central line thereof and lateral portions of the aeroplane.

As here shown the aeroplane has depending members E E at its opposite sides and slightly ahead of the transverse line coincident with the post D. This duplicated depending member E has connection with the aeroplane in the same manner as the aforementioned block b; that is the aeroplane has its bracket a⁵, with slideway a⁶ therein, shaft supports a⁷, a⁷, and screw shaft a⁸—the upper part of the member E being comprised in a screw connected block or section a⁹, fitted and movable in the slideway. Each depending member E has a hole 20 low bulb f at its lower end for receiving a ballasting material therein, such bulb having an internally threaded neck by means of which it is detachably connected.

F F represent mediums of connection extending between lower portions of the depending members E E, and a slidable collar g at or near the base of the post D, the same having connections with said parts; said connections has each a spring portion h and 30 a chain or other non-elastic portion h²; and the aforementioned collar is capable of a slight vertical movement as guided on the post and in rising its movement is against the reaction of a spiral spring g² for one end 35 of which the stop or shoulder g³ is provided.

The appliances and connections described operate to normally maintain the aeroplane with its transverse line horizontal; but in the flight of the machine when the body or 40 frame thereof, which is supported or hung from the aeroplanes in a pendulous manner, is relatively at an angle (in the cross sectional aspect) to the aeroplanes, the resilient connections may come and go to accord 45 with the degree of tilting, either to a downward leftward inclination or to a downward rightward inclination of the plane. In other words, the frame and motors thereon will be generally carried level, even although the 50 planes are tilted transversely in either direction. By having the connections between the posts D D and the aeroplanes and between the paired depending members E E and the aeroplanes longitudinally adjustable, the positioning of the aeroplanes relatively to each other and for their properly balanced support at the upper ends of the 55 posts may be practicably accomplished.

The machine is provided with a cock-pit 60 housing or cabin G at the center thereof in which the controlling members for the several instrumentalities comprised in the machine are located.

J represents an upstanding lever to which 65 forwardly and rearwardly extending con-

nnecting rods j are pivoted, such rods having at their forward and rear ends respectively connections with the upstanding arm of bell crank levers j², to the lower horizontal arms of which connection is made by link j³ or 70 suitably otherwise with the lower ends or vertical thrust rods j⁴ which extend upwardly through guide tubes j⁵ of the frame and have universal joint connections (j⁶ representing the universal joints) with rear 75 under portions of the aeroplane. By swinging the lever J more or less the inclinations of the aeroplanes are acquired simultaneously and of corresponding degree.

The pair of motors K K are mounted on 80 the lower platform-like portions of suspension frame M which are hung from and are longitudinally adjustably movable relatively to the main frame A. The motors are to be so positioned as to be one ahead and the 85 other to the rear of the center of gravity of the machine, sufficiently far to counterbalance each other.

The upstanding side members m of each suspension frame which embraces and extends above the main frame or platform A are provided with opposite sets of pinions m² which engage the teeth of longitudinal rack bars m³ on main frame A. The suspension frames are suitably cross tied, braced or 90 trussed and they have pivotally mounted on upper parts thereof reversed pivoted pawls or dogs m⁴ to be engaged in the rack teeth for holding the motor suspension frames in 95 their given set positions.

k represents a pair of levers in the cockpit to which connecting rods k², k² are pivoted, such rods being also pivoted to the motor suspension frame, and so that by the operations of either of the levers k individually the motor suspension supports may be independently adjustably positioned. Of course, in order to permit either suspension frame to be moved along the main frame, it is necessary to manually temporarily 100 throw the dogs m⁴ out of their rack teeth engagements.

The bladed propellers P are mounted on horizontal shafts P² therefor in hangers o at the forward and rearward ends of the 115 machine,—both propellers being provided to work simultaneously and to drive the machine forwardly,—that is from left to right as Figs. 1 and 2 are viewed. For the propellers, driving means are provided which are adapted to be placed in and out of clutch engagement with the shaft Q which is driven by the duplicated motors K.

The motor shafts q have sprocket wheels Q² thereon and sprocket wheels q³ are 125 mounted for rotation on the motor suspension frame M, such wheels moving horizontally and longitudinally in unison with the suspension frames which are capable of the fore-and-aft adjustments hereinbefore men- 130

tioned and such sprocket wheels q^3 have spline engagements with the engine driven shaft Q so as to be capable, when driven by the sprocket chains q^4 of driving the shaft 5 Q, which has suspensions in the hangers o^1 at front and rear of the machine and also in the intermediately positioned hangers o^2 .

The shaft Q is by preference continuous from end to end of the machine, but this is 10 by no means requisite as separate and duplicated shafts individual to the respective motors might with satisfactory results be employed. Appurtenant to each propeller is a countershaft R horizontally mounted in the 15 hangers o and having sprocket wheel r around which runs sprocket chain r^2 which drives the sprocket wheel r^3 affixed to the propeller shaft. On the inner ends of the countershafts R are affixed sprocket wheels 20 s which by the chain s^2 have driving connection with the sprocket wheels s^3 which are loose on the engine driven shaft Q and with which are associated the clutches t including the spline and slidable collars, such clutches 25 and operating collars being of any usual or approved type. The levers u are provided in coaction with the clutch collars and the pair of connecting rods u^2 are pivoted at their outer ends to both of the levers u and 30 at their inner ends are both connected to the operating lever u^3 at the center of the machine, — the organization being such that when the lever u^3 is swung in one direction the mechanism for driving the propellers is 35 in clutch, and both propellers will, therefore, be located while, of course, when the lever u^3 is suitably reversely swung, the propeller drive will be out of clutch.

The rudder T is located adjacent the 40 center of the machine and above the aeroplane. It is carried on an upstanding shaft or post v to which an operating member v^2 , such, for instance, as a hand wheel, is provided.

As represented by dotted lines in Fig. 1, 45 and in detail section Fig. 4, the aeroplanes have opposite sets of depending ribs w having a front to rearward trend; but instead of being, as they might be employed with a degree of advantageous result, they are for 50 even better results arranged obliquely and those at opposite sides of the central longitudinal line of the machine convergently to each other. These ribs as shown are provided at and depending below the underside 55 of the aeroplane, but an inversion of this arrangement might be made.

I claim:

1. An aerial machine including a main frame, an upstanding support provided at 5 the longitudinal median of such frame, an aeroplane jointed to an upright support whereby it may oscillate transversely, resilient mediums having anchored connections with the lower portion of the upstanding support and having connections with oppo-

site lateral portions of the aeroplane, and means for positioning the aeroplane in any fore-and-aft inclination.

2. An aerial machine including a main frame, an upstanding support provided at 70 the longitudinal median thereof, an aeroplane jointed to the upper portion of the upright support whereby it may oscillate transversely, members connected with and depending below the lateral portion of the 75 aeroplane, resilient mediums having anchorages at the longitudinal median of the main frame, and having connections with portions of said depending members below the aeroplane, and means for placing and 80 confining the aeroplane in any fore-and-aft inclination.

3. An aerial machine including a main frame, an upstanding support at the longitudinal median thereof, an aeroplane jointed to the upright support whereby it may oscillate transversely, a member slidably movable relatively to a lower portion of the upstanding support, resilient means against which said member is slidable in the upward 90 direction, and resilient mediums having connections at their inner ends with said slid- 95 able member and having connections with opposite lateral portions of the aeroplane.

4. An aerial machine including a main 95 frame, an upstanding support at the longitudinal median thereof, an aeroplane jointed to the upright support whereby it may oscillate transversely, a member slidably movable relatively to a lower portion of the 100 upstanding support, resilient means against which said member is slidable in the upward direction, resilient mediums having connections at their inner ends with said slid- 105 able member and having connections with opposite lateral portions of the aeroplane, and means for placing the aeroplane in any fore-and-aft inclination.

5. An aerial machine including a main 110 frame, an upstanding support at the longitudinal median of the frame, an aeroplane jointed to oscillate on the upstanding support for acquiring its fore-and-aft inclination and also adapted to rock transversely, means for varying the center of oscillation, 115 and resilient means against the resistance of which the plane has its transverse rocking movements.

6. An aerial machine including a main 120 frame, an upstanding support at the longitudinal median of the frame, an aeroplane mounted to oscillate on the upstanding support for acquiring its fore-and-aft inclination and also adapted to rock transversely, 125 resilient means against the resistance of which the plane has its transverse rocking movements, and pendulous weighting and plane balancing means forward of the center of oscillation.

7. An aerial machine including a main 130

frame, an upstanding support at the longitudinal median of the frame, an aeroplane mounted to oscillate on the upstanding support for acquiring its fore-and-aft inclination and also adapted to rock transversely, resilient means against the resistance of which the plane has its transverse rocking movements, pendulous weighting and plane balancing means forward of the center of oscillation, means for varying longitudinally the center of oscillation, and means for longitudinally variably positioning the plane-balancing means.

8. An aerial machine including a main frame, an upstanding support at the longitudinal median of the frame, an aeroplane mounted to oscillate on the upstanding support for acquiring its fore-and-aft inclination and also adapted to rock transversely, resilient means against the resistance of which the plane has its transverse rocking movements, duplicated pendulous weighting and plane balancing means forward and at opposite sides of the center of oscillation, means for varying longitudinally the center of oscillation, and means for individually longitudinally variably positioning the duplicated plane-balancing means.

9. In an aerial machine, a supporting frame, an upstanding support at the longitudinal median thereof, an aeroplane universal-joint-connected to the upstanding support for fore-and-aft oscillation, and transverse rocking movement, resilient means against the resistance of which the plane transversely rocks, a thrust rod having a universal-joint connection with the plane, at a point, in the longitudinal line of the latter distant from the upstanding support, manually operable means for moving the thrust rod, and means for confining such thrust rod against movement.

10. In an aerial machine, a main frame, an upstanding support at the longitudinal median thereof, an aeroplane having on its central longitudinal line a bracket comprising a longitudinal downwardly open slideway and shaft supports to the forward and rear of the slideway, a block movably guided in the slideway, a screw shaft rotative in said shaft support and having a screw engagement with the block, a universal joint connecting the said block and said upstanding support, means for positioning the plane in its desired fore-and-aft inclination, and resilient means against the resistance of which the plane may have its transverse rocking movement.

11. In an aerial machine, a main frame, an upstanding support at the longitudinal median thereof, an aeroplane having on its central longitudinal line a bracket comprising a longitudinal downwardly open slideway and shaft supports forward and to the rear of the slideway, a block movably guided

in the slideway, a screw shaft rotative in said shaft supports and having a screw engagement with the block, a universal joint connecting the said block and said upstanding support, means for positioning the plane in its desired fore-and-aft inclination, a collar vertically slidable on the upstanding support, a spring against the resistance of which the collar has its sliding movement in an upward direction, and connections including springs secured to said collar and extending upwardly and outwardly and having connections with the plane at opposite side portions of the latter.

12. In an aerial machine, a main frame, an upstanding support at the longitudinal median thereof, an aeroplane universal-joint-connected with the upstanding support, and having, at opposite side portions thereof and forward of the upstanding support, depending brackets each comprising a longitudinal downwardly open slideway and shaft-supports forward and to the rear of the slideway, a block movably guided in each slideway, a screw rotative in each set of the shaft supports and screw engaging the block, depending members supported by opposite pairs of such blocks, and resilient mediums connected to the depending members, and having anchorages at the longitudinal median of the machine.

13. In an aerial machine, a main frame, an upstanding support at the longitudinal median thereof, an aeroplane universal-joint-connected with the upstanding support, and having, at opposite side portions thereof and forward of the upstanding support, depending brackets each comprising a longitudinal downwardly open slideway and shaft-supports forward and to the rear of the slideway, a block movably guided in each slideway, a screw rotative in each set of the shaft supports and screw engaging the block, depending members supported by opposite pairs of such blocks, and resilient mediums connected to the depending members, and a member at the longitudinal median of the machine, and vertically movable yielding means against the resistance of which said members vertically move,—said resilient mediums having at their inner ends connections with said vertically movable member.

14. In an aerial machine, a main frame, an upstanding support at the longitudinal median thereof, an aeroplane universal-joint-connected with the upstanding support, and having, at opposite side portions thereof and forward of the upstanding support, depending brackets each comprising a longitudinal downwardly open slideway and shaft-supports forward and to the rear of the slideway, a block movably guided in each slideway, a screw rotative in each set of the shaft supports, and screw engaging the block, depending members supported by opposite

pairs of such blocks and provided with ballasting receptacles, and resilient mediums connected to the depending members, and having anchorages at the longitudinal median of the machine.

15. In an aerial machine, a frame having an upstanding support at its longitudinal median, an aeroplane universal-joint-connected at an intermediate portion of its longitudinal median to the upstanding support, and means for longitudinally varying such point of connection, and resilient means, against the yielding resistance of which the plane may have its sidewise rocking movements.

16. In an aerial machine, a frame having an upstanding support at its longitudinal median, an aeroplane universal-joint-connected at an intermediate portion of its longitudinal median to the upstanding support, and means for longitudinally varying such point of connection, depending members longitudinally adjustably connected to the aeroplane at opposite side portions thereof, and at different portions in the length therefrom, from the connection of the plane with the upstanding support, and resilient means, against the yielding resistance of which the plane may have its sidewise rocking movements.

17. In an aerial machine, a frame, an elevated support thereon, an aeroplane universally-joint-connected to said support, resilient means against the resistance of which the plane is transversely tiltable, a bell crank

lever, means connected with one arm thereof for imparting a swinging motion thereto, and a thrust rod connected to the other arm of the bell crank and universal-joint-connected to the plane at a point longitudinally 40 distanced from the connection of the plane with the elevated support.

18. In an aerial machine, a frame, elevated supports thereon, one in advance of the other, aeroplanes universally joint-connected to said supports, resilient means against the resistance of which the planes are transversely tiltable, and means connected with both of the planes for imparting fore-and-aft inclinations thereto simultaneously and in corresponding degrees.

19. In an aerial machine, a frame, elevated supports thereon, one in advance of the other, aeroplanes universal-joint-connected to said supports, resilient means 55 against the resistance of which the planes are transversely tiltable, means connected with both of the planes for imparting fore-and-aft inclinations thereto simultaneously and in corresponding degrees, and ballasting 60 devices on opposite lateral portions of the planes and means for adjusting said ballasting devices individually and longitudinally.
